CLAIM

The ornamental design for a sprayer, substantially as shown and described.

DESCRIPTION

FIG. 1 is a perspective view of a sprayer showing my new design;

FIG. 2 is a front elevational view thereof;

FIG. 3 is a side elevational view thereof, the opposite side being identical;

FIG. 4 is a rear elevational view thereof; and

FIG. 5 is a top plan view thereof.

The broken-away showing of the supply tube in FIGS. 1, 2, 3 and 5 is to indicate indeterminate length.

FIG. 2

FIG. 5

FIG. 4
